UNITED STATES PATENT OFFICE.

HARRY E. KERR AND WILLIAM J. BARBER, OF CLEVELAND, OHIO, ASSIGNEES TO
CLEVELAND GAS BURNER & APPLIANCE CO., OF CLEVELAND, OHIO.

DESIGN FOR A GAS-BURNER.

53,918.

Specification for Design.

Patented Oct. 7, 1919.

Application filed May 26, 1919. Serial No. 299,988. Term of patent 14 years.

To all whom it may concern:

Be it known that we, HARRY E. KERR and WILLIAM J. BARBER, citizens of the United States, residing at Cleveland, in the county of Cuyahoga and State of Ohio, have invented a new, original, and ornamental Design for a Gas-Burner, of which the following is a specification, reference being had to the accompanying drawing, forming part thereof.

Figure 1 is a top plan view, Fig. 2 a side elevation, and Fig. 3 a bottom view of a gas burner showing our new design.

We claim:

The ornamental design for a gas burner, as shown.

HARRY E. KERR.
WILLIAM J. BARBER.
